Attorney.

UNITED STATES PATENT OFFICE.

GEORGE C. WORTMAN, OF DENVER, COLORADO.

HOLDER FOR RAILWAY-RAIL SPIKES.

1,333,235.

Specification of Letters Patent.

Patented Mar. 9, 1920.

Application filed October 21, 1918. Serial No. 258,967.

To all whom it may concern:

Be it known that I, GEORGE C. WORTMAN, a citizen of the United States, residing at 137 West Irvington Place, in the city and county of Denver and State of Colorado, have invented certain new and useful Improvements in Holders for Railway-Rail Spikes; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means for holding the spikes of railway rails against upward movement or from working loose and moving up in response to the vibration imparted to the rails while trains are passing. Much difficulty has been experienced by railway companies due to the fact that the spikes work up, with the result that men are constantly needed to watch the tracks and keep these spikes down in their normal position, whereby they operatively engage the rails.

My further object is to provide a device of this character which shall be simple in construction, economical in cost, reliable, durable and efficient in use, and to these ends the invention consists of the features, arrangement and combinations hereinafter described and claimed, all of which will be fully understood by reference to the accompanying drawing, in which is illustrated an embodiment thereof. In this drawing:

Figure 1 is a section of a railway rail and tie, showing my improvement applied. Fig. 2 is a similar section, omitting the tie and illustrating the first step in applying the device.

Fig. 3 is a perspective view of a rail and tie equipped with my improvement.

Fig. 4 is a section taken on the line 4—4, Fig. 2, viewed in the direction of the arrows.

Fig. 5 is a section taken on the line 5—5, Fig. 4, shown on a larger scale.

Fig. 6 is a perspective view of the device shown in detail.

Fig. 7 is a similar view of a locking key employed in connection with my improvement.

The same reference characters indicate the same parts in all the views.

Let the numeral 5 designate a railway

rail of any suitable construction; and 6, an ordinary wood tie. My improvement consists of a plate, 7, placed between the base, 8, of the rail, and the tie, this plate having an upturned flange, 9, on one edge, adapted to engage the heads, 10, of spikes, 12, the latter being of ordinary or any suitable construction for connecting the rails with the track ties. The plate on the side adjacent the flange, 9, is provided with slots, 13, whereby, after the spikes are driven into place in the tie on this side of the rail, the plate, 7, is moved laterally to cause the flange or lip, 9, to engage the heads of the spikes from above. On the opposite side of the rail the plate is provided with spike openings, 14, in which the spikes fit, or approximately fit, these holes being in the spike-receiving position after the plate has been shifted laterally to bring the flange, 9, into engagement with the spike heads on the opposite side, as just explained.

Mounted on an extension of the plate, 7, adjacent the spike-holes, 14, is a spike-holding member, 15, which is connected with the plate by rivet pins, 16, which pass through slots, 17, formed in the member 15, and are of sufficient length to permit the shifting of this member to cause its inner raised extremity, 18, to engage the heads of the adjacent spikes, as shown in Figs. 1 and 3. As illustrated in the drawing, the rivet pins, 16, are fast on the plate 7, and after the member 15 is applied from above, the upper ends of the pins are upset to form heads, 19, which extend beyond the slots, 17, on opposite sides, thus holding the member 15 in proper cooperative relation with the plate and in close contact therewith by allowing the member 15 to slide freely, as circumstances may require.

The outer extremity of the plate on the side adjacent the member 15 is provided with a rib or upwardly projecting part, 20, of any suitable size or strength that may be required. When the member 15 is shifted to the spike holding position, as shown in Figs. 1 and 3, a key, 21, is driven into place between the rib, 20, and the outer edge of the member 15, the inner face of the rib and the opposing face of the member 15 forming a space having inclined walls, the said space being narrowest at the top. These parts are also preferably longitudinally inclined to receive the key, 21, which is wedge-shaped longitudinally and also dovetailed to enter the space between the rib 20 and the

opposing edge of the member 15. Furthermore, the side walls of the dovetailed groove into which the key 21 is driven are preferably roughened, as shown at 22 (see Figs. 4 and 5), this roughening preferably consisting of shallow points, extending in the direction toward which the key moves as it is driven into place, these points being thus arranged to normally retard the reverse movement of the wedge. This roughness, however, is of such character that the keys 21, which are preferably composed of wood, may be driven out by the use of suitable devices. One of these points 22 is illustrated in Fig. 5, but is exaggerated for the purpose of better illustrating the construction. It is believed that very slight projections into the path of the key will perform the required function and allow the key to move inwardly into position with reasonable freedom, but will prevent return or outward movement except by design.

From the foregoing description it is believed the use of my improvement and the manner of applying it will be readily understood.

It may be assumed that the plate 7 is in the position shown in Fig. 2, and that the spikes 12 on the side of the rail corresponding with the flange, 9, of the plate, 7, are driven into the tie, 6, whereby the head, 10, of the spike is caused to overlap the base of the rail on the adjacent side. The plate, 7, is then shifted toward the right to bring the flange or lip, 9, into engagement with the heads, 10, of the adjacent spikes, as shown in Figs. 1 and 3. The spike-holes, 14, on the opposite side of the rail, will then be in position to receive spikes 23, which are driven into place, after which the member 15 will be moved from the position shown in Fig. 2 to the position shown in Figs. 1 and 3, after which the key, 21, is driven into place, thus securely locking the member 15 in the spike-holding relation.

While I have thus shown but one construction for securing the key 21 against accidental longitudinal reverse movement, it must be understood that any suitable means adapted to properly perform this function may be used. It is assumed that the key, 21, is composed of hard wood, though it must be understood that any suitable material may be employed.

Having thus described my invention, what I claim is:

1. A holder for the spikes of railway rails, comprising a base plate upon which the rail rests, the plate having openings for the spikes, these openings on one side being elongated to permit the shifting of the plate laterally when the spikes are in place, the plate having an inwardly projecting member for engaging the spikes after the shifting of the plate, the plate also having a member on the opposite side from the first named member, which is movable into engagement with the adjacent spikes, to hold the latter against upward movement away from the rail.

2. A holder for the spikes of railway rails, comprising a base plate upon which the rail rests, the plate having openings for the spikes, these openings on one side being elongated to permit the shifting of the plate laterally when the spikes are in place, the plate having an inwardly projecting member for engaging the spikes after the shifting of the plate, the plate also having a member on the opposite side from the first named member, which is movable into engagement with the adjacent spikes, to hold the latter against upward movement away from the rail.

3. A holder for the spikes of railway rails, comprising a base plate upon which the rail rests, the plate having openings for the spikes, these openings on one side being elongated to permit the shifting of the plate laterally when the spikes are in place, the plate having an inwardly projecting member for engaging the spikes after the shifting of the plate, the plate also having a member on the opposite side from the first named member, which is movable into engagement with the adjacent spikes, to hold the latter against upward movement away from the rail, and means for securing the movable member in the spike-holding position.

4. A holder for the spikes of railway rails, comprising a base plate upon which the rail rests, the plate having openings for the spikes, these openings on one side being elongated to permit the shifting of the plate laterally when the spikes are in place, the plate having an inwardly projecting member for engaging the spikes after the shifting of the plate, the plate also having a member on the opposite side from the first named member, which is movable into engagement with the adjacent spikes, to hold the latter against upward movement away from the rail, and means for securing the movable member in the spike-holding position, said means including a rib formed on the plate and a key inserted between the rib and the adjacent part of the movable member.

5. Spike-holding means, comprising a plate having a spike-holding member slidably connected therewith, means permanently holding said member from movement away from said plate in all positions, both operative and inoperative, and means for securing said member in spike-holding position.

6. The combination with a rail and tie,

- of a plate adapted to be arranged between the rail and tie and equipped on opposite sides of the rail with spike-holding members, one of said members being movable on the plate, and means for retaining said movable member in the adjusted position, said means comprising a stop on the plate and a key inserted between said stop and the adjacent part of the movable member.
- 10 7. The combination with a rail and tie, of a plate adapted to be arranged between the rail and tie and equipped on opposite sides of the rail with spike-holding members, one of said members being movable on the plate, and means for retaining said movable member in the adjusted position, said means comprising a stop on the plate and a key inserted between said stop and the adjacent part of the movable member, the stop and the said part of the movable member being shaped to form a dovetailed space for the key.
- 15 8. The combination with a rail and tie, of a plate, adapted to be arranged between the rail and tie and equipped on opposite sides of the rail with spike-holding members, one of said members being movable on the plate, means for retaining said movable member in the adjusted position, said means comprising a stop on the plate and a key inserted between said stop and the adjacent part of the movable member, the stop and the said part of the movable member being shaped to form a dovetailed space for the key, and means for retaining the latter in place against longitudinal movement.
- 20 9. Spike-holding means, comprising a plate having a spike-holding member slidably connected therewith, means permanently mounted on said plate and passing through said member to hold said member from movement away from said plate, and means for securing said member in spike-holding position.
- 25 45. 10. A holder for the spikes of railway rails, comprising a plate arranged between the rail and tie, having members carried by the plate and adapted to engage the spike heads to prevent upward movement, one of said members being adjustable to assume the spike-retaining position, and means for retaining the last named member in the adjusted position, said means comprising a rib on the plate and a key adapted to be driven between the said rib and the adjacent spike-holding member.
- 30 60. 11. A holder for the spikes of railway rails, comprising a plate arranged between the rail and tie, having members carried by the plate and adapted to engage the spike heads to prevent upward movement, one of said members being adjustable to assume the spike-retaining position, and means for retaining the last named member in the adjusted position, said means comprising a

rib on the plate and a key adapted to be driven between the said rib and the adjacent spike-holding member, the parts being equipped to hold the key in place.

12. Spike-holding means, comprising a plate having a spike-holding member, movably connected therewith, and means for securing said member in the spike-holding position, said means comprising a rib on the plate and a key inserted between the rib and the movable member.

13. Spike-holding means, comprising a plate, a spike-holding member, one of said elements being slotted, and retaining means permanently secured to one element and engaging a slot in the other.

14. Spike-holding means, comprising a plate and a spike-holding member, one of said elements having an elongated opening and the other an opening to receive a retaining device, and a retaining device passing through the openings in the two elements and permanently mounted therein in all operative and inoperative positions of the assembled device.

15. Spike-holding means, comprising a plate and a spike-holding member, one of said elements having an elongated opening and the other an opening to receive a retaining device, and a retaining device passing through the openings in the two elements, the plate having a rib, and a key inserted between the rib and the adjacent part of the spike-holding member.

16. Spike-holding means, comprising a plate and a spike-holding member, one of said elements having an elongated opening and the other an opening to receive a retaining device, and a retaining device passing through the openings in the two elements, the plate having a rib, and a key inserted between the rib and the adjacent part of the spike-holding member, one of the parts engaged by the key being provided with means to prevent accidental displacement of the key in a longitudinal direction.

17. Spike-holding means, comprising a plate and a spike-holding member, one of said elements having an elongated opening and the other an opening to receive a retaining device, and a retaining device passing through the openings in the two elements, the plate having a rib, and a key inserted between the rib and the adjacent part of the spike-holding member, one of the parts engaged by the key being provided with means to prevent accidental displacement of the key in a longitudinal direction, the parts between which the key is inserted being arranged to form a space dovetailed in cross section and tapering longitudinally, the key being formed approximately of counterpart shape.

In testimony whereof I affix my signature.
GEORGE C. WORTMAN.
